Oliver Tompkins, of Brooklyn, N.Y.
Letters Patent No. 1338, dated Oct. 9, 1860.

The schedule referred to in these Letters Patent and making part of the same.

To all whom it may concern:

Be it known that I, Elias Tompkins, of Brooklyn, in the County of Kings, and State of New York, have invented a design for Heater Fronts, which I have described in the following specification and illustrated in its accompanying drawings, with sufficient clearness to enable competent and skillful workmen, in the arts to which it pertains, or is most nearly allied, to make and use my design —

My said design consists in the combination and arrangement of various architectural mouldings so adapted and placed as to produce a new design for Heater fronts, as hereinafter more fully set forth —

The accompanying drawing is a front elevation.

The front of the said design consists of two fluted columns, 1 and 2, connected with a curved centre piece 3 and which is so curved as to allow it to project in advance of the columns as shown upon the drawing. At the bottom of this centre piece and columns is a moulding 4, projecting from face of the columns and centre piece and under which is placed the bases 5 and 6, of the columns 1 and 2, and on which bases are the moulded panels, 7 and 8.

The top of the columns are surmounted by the mouldings 9 & 10. The upper part of the centre piece is curved above the top of the columns 1 and 2, and is surmounted by the moulding 11, and which mouldings 9, 10 and 11, project from the face of the columns and centre piece. 12 and 13, are two panels with their mouldings placed on each side of the centre piece to relieve the dead space between the doors and the columns.

The upper part of the centre piece 3 is pierced with the spaces 13, which is closed by a slide to regulate the draught of the fire. 14 & 14, are two doors with curved tops for the introduction of coal to the cylinder.

The lower part of the centre piece 3, is provided with a series of spaces 15, which is supplied with a slide to regulate the current of cold air around the cylinder. 16 and 16, are two doors in the lower part of the front and hinged to the bases of the columns for the purpose of cleaning the grate and the removal of the ashes.

The particular improvements which constitute my said design and which I claim as having been originally and first invented by me, are, the combination and arrangement of the various architectural mouldings, so as to produce by their combined artistic effect and their relative positions the design
